UNITED STATES PATENT OFFICE.

GEORGE M. LITTLE, OF PITTSBURGH, PENNSYLVANIA, ASSIGNOR TO WESTINGHOUSE ELECTRIC & MANUFACTURING COMPANY, A CORPORATION OF PENNSYLVANIA.

RESISTOR AND METHOD OF MAKING THE SAME.

Application filed September 27, 1922. Serial No. 590,753.

This invention relates to resistors, more particularly to resistors of the carbon-pile type and to methods of making the same.

It is common practice to utilize plates of carbon or of refractory material containing carbon in contact with each other to provide a resistor for carrying current in electric furnaces. The resistance thereof is caused mainly by the poor contact between the plates. Such resistors have advantages in that they are capable of withstanding a considerable amount of heat without softening, melting, volatilizing or otherwise deteriorating in service. However, they are expensive to manufacture, require a considerable time to assemble and are relatively fragile and subject to breaking in handling and service.

The present invention is directed to a resistor of this type, it being among the objects thereof to provide a carbon-pile resistor which shall be simple in construction, inexpensive to assemble and efficient in service.

In practicing my invention, I provide a series of plates made of plastic material such as coke, pitch and oil thoroughly mixed and pressed in close contact with each other in the plastic state and baked in the assembled position. The several layers of material constituting the plates are prevented from sticking together by various means. To accomplish this, the surface of a plate may be cooled, wetted, or dusted with suitable material and the next layer placed thereon. To insure the plates holding together while being baked, I may mold small pieces of iron wire or strips of asbestos therein.

My resistor may be produced in the following manner. I provide a wooden mold of the size and contour of the finished resistor. I then make a plastic mass by melting 35 parts of coal-tar pitch, adding 100 parts of calcined petroleum coke powder and a little summer oil thereto and then heating and mixing the ingredients. A sufficient amount of the plastic mass is tamped into the mold to provide a plate of any desired thickness. The exposed surface thereof is then treated to render the same non-adherent in any suitable manner. The surface may be either cooled, moistened with a little water, or coke dust, lampblack, powdered graphite or the like may be dusted thereon. Another portion of the plastic mass

is then tamped in and the steps are repeated until the desired number of plates have been formed. The assembly is then removed from the mold and baked in an oven to the desired degree.

This method provides a resistor in which the irregularities in the contacting surfaces of adjacent plates are complementary, thus avoiding an uncertain fit between plates and obviating the necessity of assembling the plates after baking. The cost of a structure of this kind is materially less than that of resistors of the old type.

In order to obtain a resistor which shall have a high resistance and great mechanical strength, it was customary to provide portions of relatively high resistance and portions mechanically strong. This has been accomplished by providing plates of hard material and alternating the same with loose granules of resistor material. I may obtain the same result by the above process or in any other suitable manner by making alternate plates of hard and of soft resistor material.

In the accompanying drawings constituting a part hereof and in which like reference characters indicate like parts,

Fig. 1 is a cross-sectional view of a resistor made in accordance with my invention, and

Fig. 2 is an enlarged cross-sectional view of a portion thereof, showing the irregularities in the surface of the plates.

I provide plates 1 of a relatively hard resistor material and assemble between alternate plates 1 the plates 2 of resistor material which are soft and have a relatively higher resistance than plates 1. Electrodes 3 and 4, having suitable terminals 5 secured thereto, make contact with the end plates of the carbon pile thus formed.

My new method of forming all the plates of a resistor simultaneously results in a structure, in which the irregularities 6 of adjacent plates interlock and provide a construction in which the plates make contact over substantially the entire surfaces thereof.

Although I have described my invention, setting forth certain details of construction and a composition which I may utilize, it is to be understood that my invention is not limited to such details. For instance, compositions other than that described are suitable for my purpose and all of the plates

may be of the same material or a plurality of compositions may be utilized for the several plates. The irregularities 6 in the surfaces of the plates are those occurring normally in the manufacture thereof but, if desired, I may utilize a plunger adapted to stamp depressions into the surfaces of the plates to lock the same together. These and other changes may be made in the details of 10 construction of my invention within the scope thereof.

I claim as my invention:

1. A resistor comprising adjacent contacting plates of resistor material, the irregularities in the contacting surfaces of adjacent plates being complementary, alternate plates of said resistor being of different types of resistor material.

2. A resistor comprising adjacent contacting plates of carbonaceous resistor material, alternate plates being hard and soft.

3. A method of making resistors which comprises providing a plastic mass of resistor material, molding a plate therefrom, rendering the surface of said plate non-adherent and molding another plate thereon.

4. A method of making resistors which comprises providing a plastic mass of resistor material, molding a plate therefrom, rendering the surface of said plate non-adherent, molding another plate thereon, and repeating the cycle of operations.

5. A method of making resistors which comprises providing a plastic mass of resistor material, molding a plate therefrom, covering the surface of said plate with ma-

terial capable of rendering the same non-adherent and molding another plate thereon.

6. A method of making resistors which comprises providing a plastic mass of resistor material, molding a plate therefrom, covering the surface of said plate with carbon dust to render the same non-adherent, and molding another plate thereon. 40

7. A method of making resistors which comprises providing a plastic mass of resistor material, molding a plate therefrom, covering the surface of said plate with carbon dust to render the same non-adherent, molding another plate thereon and repeating 50 the cycle of operations.

8. A resistor comprising adjacent contacting plates of resistor material, the irregularities in the contacting surfaces of adjacent plates being complementary, alternate plates being composed of hard resistor material consisting mainly of carbon and the remaining plates being composed of soft resistor material consisting mainly of carbon. 55

9. A resistor comprising adjacent contacting plates of resistor material of different degrees of hardness, alternate plates being composed of hard resistor material containing a substantial amount of carbon and the remaining plates being composed of soft resistor material containing a substantial amount of carbon. 60 65

In testimony whereof I have hereunto subscribed my name this 21st day of September 1922.

GEORGE M. LITTLE.
